CHAIR

Robert L. Buscher, 2249 Roth St., Madison, Wis.

Filed May 1, 1961, Ser. No. 64,977

Term of patent 14 years

(Cl. D15—1)

FIGURE 1 is a front perspective view of a chair showing my design;

FIGURE 2 is a rear perspective view;

FIGURE 3 is a side perspective view thereof; and

FIGURE 4 is a fragmentary front elevation thereof.

The design is characterized by the substantially keyhole-shaped back portion in combination with the specific configuration of the leg brace all as shown.

I claim:

The ornamental design for a chair, as shown and described.
